Primary Examiner — Jack Reickel*Assistant Examiner* — Russell Carnell Smith, Jr.(74) *Attorney, Agent, or Firm* — Westbridge IP LLC(57) **CLAIM**

The ornamental design for an LED display screen, as shown and described.

DESCRIPTION

FIG. 1 is a front perspective view of an LED display screen showing my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The dash-dash broken lines in the drawings depict the portions of the LED display screen which form no part of the claimed design.

1 Claim, 8 Drawing Sheets(56)
